UNITED STATES PATENT OFFICE

JOHN F. KOEPPEN, OF MARION, INDIANA

DESIGN FOR A BOTTLE

Application filed August 23, 1932. Serial No. 44,672. Term of patent 7 years.

To all whom it may concern:

Be it known that I, JOHN F. KOEPPEN, a citizen of the United States, residing at Marion, in the county of Grant and State of Indiana, have invented a new, original, and ornamental Design for a Bottle, of which the following is a specification, reference being had to the accompanying drawing, forming part thereof.

I claim:—

The ornamental design for a bottle as shown.

JOHN F. KOEPPEN.
